CLAIM

The ornamental design for a pair of socks, as shown and described.

DESCRIPTION

FIG. 1 is a front perspective view of a pair of socks according to a first embodiment;

FIG. 2 is a left side elevation view of the pair of socks of FIG. 1;

FIG. 3 is a right side elevation view of the pair of socks of FIGS. 1-2;

FIG. 4 is a top plan view of the pair of socks of FIGS. 1-3;
FIG. 5 is a bottom plan view of the pair of socks of FIGS. 1-4;
FIG. 6 is a front elevation view of the pair of socks of FIGS. 1-5; and,

FIG. 7 is a rear perspective view of the pair of socks of FIGS. 1-6.

A mirror image (not shown) of the pair of socks of FIGS. 1-7 constitutes a second embodiment.

The dashed broken lines are included for the purpose of illustrating environment of the design and form no part of the claimed design.
